FREDERICK OTTO BENDIX AND EMILE BENDIX, OF NEW ORLEANS,
LOUISIANA.

FILTER.

SPECIFICATION forming part of Letters Patent No. 779,346, dated January 3, 1905.

Application filed March 7, 1903. Serial No. 146,614.

To all whom it may concern:

Be it known that we, FREDERICK OTTO BENDIX and EMILE BENDIX, citizens of the United States, and residents of New Orleans, in the parish of Orleans and State of Louisiana, have invented a new and Improved Filter, of which the following is a full, clear, and exact description.

This invention relates to improvements in water-filters; and a main object is to provide an improved means for cleaning the exterior of the filter-stone.

Other objects of the invention will appear in the general description.

We will describe a filter embodying our invention and then point out the novel features in the appended claims.

Reference is to be had to the accompanying drawings, forming a part of this specification, in which similar characters of reference indicate corresponding parts in both the figures.

Figure 1 is a section on the line 1 1 of Fig. 2, showing a filter embodying the invention; and Fig. 2 is a section on the line 2 2 of Fig. 1.

The filter comprises a casing or cylinder 5, in which the filter-stone 6 is arranged. This filter-stone is designed to be rotated when it is desired to clean it. Therefore it is mounted on a tube 7, the portion of said tube with- 30 in the stone being perforated for the inlet of water. The lower end of the tube 7 has a step-bearing 8 secured to the bottom of the casing, and the upper portion extends through a stuffing-box 9, and its upper end has a bearing in a stuffing-box 10, which provides communication with a discharge-pipe 11 for filtered water. Attached to the tube 7 is a bevel-gear 12, meshing with a bevel-pinion 13 on a shaft 14, provided with a crank-han- 35 dle 15. On the lower end of the tube 7 is a circular plate 16, having scrapers 17 on its lower side designed to stir up the sediment that may gather at the bottom of the cylinder, so that the same may be washed out 45 through a pipe 18.

The cleaning device consists of a plate 19, attached to a rod 20, mounted to turn in bearings 21 22, and the upper portion of this rod 20 extends through a stuffing-box 23 and is

provided with a handle 24. This handle may 50 be made removable, if desired. The cleaning-plate 19 is composed of seventy-five per cent. of cement and twenty-five per cent. of pulverized pumice-stone. We find such cleaning device preferable to metal, because the 55 cleaning is done when the edge of the plate is held against the stone by rubbing action instead of scraping action, as such rubbing motion will give a smooth surface to the filter-stone and will cause but very little wear 60 on the stone.

Extended vertically in the cylinder 5 and nearly the entire length thereof is an inlet-tube 25, this tube being perforated, as indicated, to discharge water which is received 65 through a pipe 26. The pipe 11 is connected to the pipe 26 by a pipe 27, and in this pipe 27 is a valve 28, which is to be closed while filtering water.

In the operation the entering water, which 70 may fill the cylinder or casing, will percolate through the filter-stone and pass into the tube 7, from which it will pass to the outlet-pipe 11. Of course the water in passing through the stone itself will be cleansed of all impuri- 75 ties.

When it is desired to clean the filter-stone, the plate 19 is to be held against the same by means of the handle 24, and then the stone is to be rotated while the water from the tube 25 is 80 sprinkled thereon. At this time the valve 28 may be opened, permitting the tube 7 and the pipes 11 and 27 to be thoroughly cleaned by the water passing through the same. The wash- 85 ing-water will of course pass out through the valved pipe 18. While the water is discharg- 90 ing through the pipe 18 a cock 29 is to be opened to admit air.

Having thus described our invention, we claim as new and desire to secure by Letters 90 Patent—

1. In a filter in combination, a cylinder, a cylindrical stone having a substantially vertical bore therein, a member disposed within said bore constituting an arbor for said stone, 95 the extremity of said member projecting below said stone and resting upon the bottom of said cylinder, and a plate rigidly carried by

said extremity in the space beneath said stone, said plate being adapted to stir the sediment accumulating in the bottom of said cylinder.

2. In a filter, in combination, a cylinder having an upper head, and a lower head with a centrally-disposed boss on the inner face thereof, a cylindrical stone mounted in said cylinder, and having a central bore, a perforated tube fitting within said bore projecting 10 downwardly therefrom and resting on said boss, a stirring-plate attached to said tube below said stone, said stirring-plate having a re-

cess in the under side thereof, means for rotating said tube, and a scraper on the face of said stone.

15

In testimony whereof we have signed our names to this specification in the presence of two subscribing witnesses.

FRED. OTTO BENDIX.
EMILE BENDIX.
